UNITED STATES PATENT OFFICE

J FORREST COBB, OF PORTLAND, OREGON, ASSIGNOR TO MOORE DRY KILN COMPANY,
A CORPORATION OF FLORIDA

APPARATUS FOR KILN-DRYING LUMBER AND OTHER SUBSTANCES

Application filed October 7, 1924. Serial No. 742,190.

My invention relates to improvements in method and apparatus for drying different substances, but particularly lumber, through the application within a kiln of a circulatory gaseous drying medium either with or without the use of artificial heat.

In respect to my invention and in any form of mechanical embodiment, it is necessary to take into account the fact that the circulatory medium takes up the comparatively heavy vapor which green wood, for example, gives off, and therefore an important feature of my invention consists in providing ascending and descending currents of the circulatory medium with minimum obstruction and without conflicting movement of the ascending and descending columns, respectively. By this means not only is a constant circulation provided, but a maximum degree of acceleration of the circulatory movement is effected, by aid of which the best results are obtained in the shortest period of time, and with equal distribution of the drying medium into effective contact with all parts of the drying stock exposed to it.

My present invention is applicable particularly to the drying of flat-piled lumber as contradistinguished from edge-piled lumber, and is specially adapted to meet the requirements of such piling of lumber or of other substances exhibited in like manner to the operation upon it of the circulatory drying medium.

My invention, within the scope above indicated, in all forms of its mechanical embodiment, comprehends a kiln. One form of embodiment is that in which the circulation of the gaseous drying medium is effected wholly, through the application thereto of heat, by the variation of the density of the circulating medium. This may be conveniently designated a system of natural circulation. Another form of embodiment is that in which the circulation is produced partly by means of heat and partly by the aid of mechanical means. Still another form of embodiment is that in which the means employed of promoting circulation is entirely mechanical, and in which such heat as it may be desirable to employ may be provided wholly or substantially

on the outside of the kiln with which, and with the source of heat also, said mechanical means is in operative communication.

What are the various objects of my invention may either be inferred from the foregoing general description or will be obvious to one skilled in the art from the following specification, wherein that which constitutes my invention is first described in detail, and is then succinctly defined in the appended claim.

Referring to the accompanying drawings, Figure I is a transverse vertical section of a kiln constituting one form of embodiment of my invention in its mechanical aspect, wherein are provided means for effecting natural circulation as aforesaid.

Figure II is a similar view of a kiln in a modified form of embodiment of my invention in its mechanical aspect, showing a kiln operative partly by natural circulation and partly by auxiliary mechanical means.

Figure III is a similar view of a kiln in a further modified form of my invention in which mechanical means of circulation exclusively are employed.

Figure IV is a longitudinal vertical section taken as on the line IV—IV of Figure I.

Figure V is a view similar to Figure IV taken as on the line V—V of Figure II.

Figure VI is a partial view similar to Figure IV taken on the line VI—VI of Figure III.

Figure VII is a perspective view of one form of fan attachment which is an example of mechanical circulation means applicable to either of the kilns shown in Figures II or III.

Referring to the numerals on the drawings, 1 indicates the side walls, 2 the top, and 3 the bottom wall, which are united one to another to form a kiln-chamber of that general type in which the material to be dried is, upon suitable conveyors, introduced at one end of the kiln, and is withdrawn from it at the other end. The kiln-chamber is provided, as usual, with end doors, not necessary to illustrate, which are opened for the passage of loaded conveyors into and out of the kiln.

as occasion requires, and which are kept closed while the kiln is in operation.

The kiln may be of any suitable and preferred design and dimensions, and may be 5 made of any suitable preferred material that is adequately fireproof, the kiln shown in the drawings being made of concrete by way of preferred example.

At any desired and convenient height above 10 the bottom wall 3, I prefer to provide a succession, at suitable intervals, of cross-beams 4 which consist of iron I-beams. The beams 4 are examples only of any suitable means of support for the material to be dried, and to 15 that end preferably carry parallel rails 5 and 6 to constitute a track extending through the kiln from end to end. Said rails are designed and adapted to accommodate conveyors or wheeled trucks 7 which are preferably united 20 in pairs as by a bunk 8 upon which the drying stock 9 is piled in substantially horizontal layers. The stock 9 is represented in the drawings by boards that are laid flat side down upon the bunks 8 and are built up in 25 vertically successive layers with non-inter-communicating spaces 10 between. Said spaces may be provided by the introduction between layers of cross piling strips, not illustrated, so that they may serve to separate 30 the successive layers of the stock without obstruction of the spaces 10 which the strips define between said layers.

The drying stock is stacked into two piles 35 separated by a clear and unobstructed medi-ally disposed vertical flue 11, which extends substantially from end to end of the kiln and is defined by the relative disposition of the piles. From the under side of the top 2, I prefer to provide upon opposite sides of the 40 two drying stock piles baffle 14 and 15. Said baffles when used are preferably made of flexible material, such, for example, as canvas of suitable weight.

The length of the bunks 8, to which is re- 45 stricted the width of the combined stock piles, is such as to provide space at their opposite ends sufficient to accommodate lateral flues 17 and 18 which, being in part defined by the piling of the stock, are disposed for 50 the most part above the cross-beams 4, and extend substantially to the stop 2. The top may be furnished with the usual succession of ventilators 19, which are provided each with the usual damper 19', or other means 55 of regulation.

Below the bunks 8, I provide rigid baffle- 60 plates or walls 20 and 21 which extend sub-stantially the full length of the kiln. They serve to divide the lower interior of the kiln-chamber below the top of the bunks 8, or, 65 in other words, the stock-supporting level, into three longitudinally disposed compartments, namely, lateral compartments 22 which communicate directly with the flues 17 and 18, respectively, and an intermediate

compartment 23 located vertically below the medial flue 11 and in direct communication therewith.

In Figure I, I show, for that form of embodiment of my invention, said lateral compartments as provided respectively, with a series of heating pipes 24 and 25 which constitute heating coils that are in operative connection with a source of heat, not illustrated. The pipes 24 and 25 may be supported in position by any suitable means, for example by pipe hangers 26 and horizontal supports 27. Above each heating coil or set of pipes 24 or 25, I prefer to provide a pipe 28 that is in operative communication with a source 75 of fluid supply, not illustrated, and which is adapted to discharge through a series of upwardly directing vents, steam, water under pressure, or compressed air, according to preference. The function of said pipe 28 is 80 that of auxiliaries to promote upward movement of the circulatory medium through the flues 17 and 18, respectively, and also to impart thereto moisture, when required for humidifying effect. A downwardly discharging 85 pipe 29 is preferably used in operative conjunction with the pipes 28.

The space defined between the baffles 20 and 21 constitutes a reservoir of capacity to 90 amply accommodate any accumulation which may occur of the circulatory medium in a moisture laden state, and thereby to remove 95 from contact with the piles of drying stock any excess moisture which the operation of the circulation may extract from the stock in the process of drying it.

I prefer also to provide in the kiln shown in Figure I a fresh air duct 30 which extends 100 preferably from end to end of the kiln, and which affords means of supply, that may be 105 regulated at will, for the introduction of fresh air from the outside into the kiln. A grid 32 is preferably provided as a cover to the duct 30 within the kiln.

In the form of kiln illustrated in Figure I 110 as described above, a constant movement of the circulatory medium is promoted, in the direction of the arrows shown in the figure, solely either by the application of heat de-115 rived from the pipes 24 and 25, or by varia-tion of density in the gaseous drying medium, which may be effected simply by the drying of the stock. Such a means of promoting circulatory movement is all that is required 120 for certain drying operations. The ascend-ing columns of the circulatory medium which rise through the flues 17 and 18 are entirely unobstructed, and are driven with sufficient force by the buoyancy of the circulatory me-125 dium derived from the heat of the pipes 24 and 25, respectively, through the short spaces 10 provided between the successive layers of the drying stock piles. The movement of the said ascending columns of the drying medi-130 um serves to prevent stagnation in any of the

spaces 10, and is aided by the downfall of the gaseous discharge from the flue 11 to keep a constant flow of the circulatory medium, however heavily laden with moisture, into the 5 medial flue 11 through which it tends, by reason of its loss of heat, to drop by gravity into the reservoir defined between the baffle walls 20 and 21. By the sole means above described, a constant circulation and recirculation, having for many purposes an all-efficient rate of movement of circulation, is produced.

Nevertheless, for the drying of some substances it may be necessary to provide, in 15 conjunction with the pipes 24 and 25, auxiliary mechanical means for promoting circulation. The combination of the heating pipes with mechanical means of circulation is shown in Figure II, for example, in which 20 the bottom wall 3 is surmounted by a floor 31 which is divided into longitudinally extended compartments 33, 34, and 35, by vertical partition walls 36 and 37. By means of apertures 38 provided in the floor 31 at intervals 25 along its length and above the several compartments, respectively, just named, provision is made for a constant circulation of the circulatory medium withdrawn from the interior of the kiln and afterwards returned 30 thereto by means of suitable fan mechanism. For example of such mechanism there is shown, in Figure VII, a fan-case 39 provided with suitable apertured delivery-ducts 40 and 41 and an intermediate suction-duct 42. The 35 ducts 40, 42, and 41, are designed to be, in effect, thrust longitudinally into the compartments 33, 34, and 35, respectively, so as to constitute the compartments 33 and 35 into separate air delivery compartments, and the 40 compartment 34 into a suction compartment.

It will be understood, of course, that the employment of the precise construction of fan mechanism shown in Figure VII is entirely optional so far as the introduction of 45 the ducts 40, 42, and 41 into the compartments 33, 34, and 35, is concerned, and that communication with said compartments may be made, if preferred, directly as by shortening the ducts last named to no more than their 50 necks 43, 44, and 45; but this is a mere mechanical variation of detail.

In Figure II, the baffles, which may be of the same shape and construction as those shown at 20 and 21 in Figure I and which 55 are for that reason designated by the same numerals, terminate above the top of the floor 31 so as to leave a space between the floor and the lower edges of said baffles, respectively. The effect of this construction is to provide 60 means of induced circulation underneath the edges of the baffles, so that any tendency at any point of stagnation of the drying medium as, for example, in the reservoir defined between the baffles 20 and 21 may be entirely 65 eliminated.

In Figure III, I show a form of embodiment of my invention in which an all mechanical means of circulation is substituted for the means of natural circulation shown in Figure I, or for the combined natural and mechanical means shown in Figure II. In that figure, vertical walls 46 and 47 springing from the bottom 3 of the kiln may be, with the effect of baffle-plates, substituted for the baffle-plates 20 and 21 heretofore described. 70 The walls 46 and 47 extend upwardly in sufficiently close proximity to the bottom of the bunks 8, where they are preferably provided, respectively, with horizontal or other flanges 48 which extend, respectively, toward the side walls 1 of the kiln, and terminating preferably in flange extensions 49, define restricted throats communicating, respectively, with the flues 17 and 18. A horizontal cross-partition 50 extends substantially the entire length of the kiln between the walls 46 and 47, and defines above it the bottom of a reservoir, equivalent in function to that already referred to as defined by the baffles 20 and 21. The horizontal wall 50 is provided at intervals along its length with apertures 51, which afford operative communication between said reservoir and a suction return-duct 52 defined below it by the conjoined walls 3, 46, 50, 75 and 47.

Lateral delivery-ducts 53 and 54 are provided between the walls 46 and 47 and the side walls 1 adjacent thereto, respectively. The ducts 52, 53, and 54, may be operatively conjoined to any suitable fan mechanism, such for example, that shown in Figure VII.

In the form of embodiment of my invention shown in Figure III, means for heating the circulatory drying medium may be provided outside of the kiln proper by heating coils, not illustrated, in operative communication with the fan-case 39. In this way all of the circulating medium may be heated, with the drying effect desired, by means located entirely or substantially outside of the 105 kiln.

The form of embodiment of my invention shown in Figure III is especially efficacious for the quick drying of green lumber or lumber in which is present a large volume of water, to effect the elimination of which, practical efficiency in the operation of the kiln demands that there shall be no stagnation of the circulatory medium or slowing down of the rate of circulation at any point 110 throughout its course.

It should be observed that the length of the spaces 10 and provision for their discharge, respectively, into the capacious medial flue 11, contribute directly to the efficiency of my apparatus for the following reasons. The spaces 10 are each filled with a stratum of heavy fluid whose inertia tends in proportion to its volume to resist movement. That tendency of resistance to motion may be 125

reduced by reduction of the transverse extent of each stratum, so as to require comparatively little driving force in the circulating medium to compel clearance of all the strata defined by the respective spaces 10, 5 and to keep the gaseous contents of said spaces constantly precipitating into the flue 11, from whence its incorporation into the main body of the circulating medium is facilitated.

10 The principle of operation above described applies if, in respect to the apparatus indicated in Figure III, for example, the movement of the mechanical means of circulation 15 be reversed, as it obviously may be, so as to convert the suction duct 52 into a single delivery duct instead of two, and the delivery ducts 53 and 54 into two suction ducts instead of one. During reversal of circulation, operation of the auxiliaries 28 and 29 is interrupted.

20 Further description of the operation of my machine than that which is presented in the foregoing specification is deemed unnecessary in this specification addressed to one skilled in the art.

What I claim is:

25 A drying-kiln comprising a kiln chamber defining-walls, and a stock-supporting track 30 extending longitudinally through the kiln-chamber, in combination with baffle walls dividing the kiln-chamber below the stock-supporting walls into three longitudinally disposed compartments, two lateral and one intermediate, baffles extending below the roof of the kiln chamber substantially in line with the baffles first above named, means for producing circulation of a gaseous medium 35 downwardly through the intermediate compartment and upwardly through the lateral compartments, by aid of medial and lateral flues formed, respectively, by the piling of stock in substantially horizontal closed layers spaced apart, one layer above another, and 40 carried upon the track, and ventilators in the roof of the kiln chamber communicating with the space defined between the baffles extending below the roof.

45 In testimony whereof, I have hereunto set 50 my hand.

J FORREST COBB.
